United States Patent

Des. 240,767
Patented July 27, 1976

240,767

MEDICAL BASIN

Jerome H. Lemelson, 85 Rector St.,
Metuchen, N.J. 08840

Filed Feb. 19, 1974, Ser. No. 430,398

Term of patent 3½ years

Int. Cl. D24—99

U.S. Cl. D83—1 U

FIG. 1.

FIG. 2.

FIG. 1 is an isometric view of a medical basin showing my new design;

FIG. 2 is a fragmentary cross-sectional view taken on the lines 2—2 of FIG. 1; and

FIG. 3 is a bottom plan view on a reduced scale.

I claim:

The ornamental design for a medical basin, as shown.
